HIGHWAY GUARD

Walter S. Edge, Pittsburgh, Pa., assignor to
 Pittsburgh Steel Company, Pittsburgh, Pa., a
 corporation of Pennsylvania

Application April 5, 1932, Serial No. 603,393

3 Claims. (Cl. 256—13.1)

My invention relates to highway guards, such as are employed as fences or deflectors to prevent vehicles leaving the roadway, on bridges, embankments, or at curves.

5 One object of my invention is to provide a guard structure that possesses a maximum capacity of resistance for a given weight of material.

Another object of my invention is to provide a 10 guard structure that is highly yieldable, and can be deflected to a greater extent than various types of guards heretofore employed, without permanent deformation of the guard strip.

Another object of my invention is to provide a 15 guard structure of such form that it will normally remain taut notwithstanding repeated changes in temperature.

Still another object of my invention is to provide an improved form of anchoring means for 20 the ends of the guard members.

A further object of my invention is to provide an improved form of yielding buffer support for guard bands.

Another object of my invention is to provide a 25 guard band or strip of improved form, and an improved manner of connecting the same to supporting posts or the like.

Some of the forms which my invention may take are shown in the accompanying drawings 30 wherein Figure 1 is a face view of a portion of a guard structure; Fig. 2 is an end view thereof, on an enlarged scale; Fig. 3 is a view taken on the line III—III of Fig. 2; Fig. 4 shows a modification of the structure of Fig. 2; Fig. 5 shows a sectional plan view of the structure of Fig. 4; Fig. 6 shows another modification of the anchoring means for the ends of the guard members; Fig. 7 is a perspective view, on an enlarged scale, of a portion of the structure of Fig. 1; Fig. 8 is a sectional plan view thereof; Fig. 9 shows one of the buffer springs which I employ, and Fig. 10 is a perspective view of another form of a buffer spring.

The structure is shown as composed of a band-like strip of mesh 10 that is supported on posts 11 and 12, which are sunk into the ground or anchored in concrete bases, the end posts 12 being provided with anchor rods 13 having turn buckles 14 for tightening the same in a manner well-known in the art.

The band 10 is shown as composed of strand wires 15 which are preferably of spring steel so that they will have considerable elasticity and can be deflected to a greater degree than ordinary iron wire, without becoming permanently distort-

ed. The wires 15 are united in unitary relation by stay wires 16 which may be either of iron or of spring steel. The strand wires 15 alternately pass in front of and behind the stay wires 16, but do not have "set" bends formed therein at the 60 points where they cross the stay wires. The stay wires 16 on the other hand are preferably pre-bent at the points shown in the drawings to form offset seats for the strand wires 15.

This arrangement not only reduces tendency of 65 the strand wires 15 to slide vertically on the stay wires but also avoids the necessity of bending the strand wires to such degree that the bends become set. In other words, if the stay wires 16 were removed, the strand wires would tend to 70 assume straight lines.

In place of some of the wires 15, I employ wires 17 that may be of iron instead of spring steel, and somewhat thicker than the wires 15. These wires 17 are welded to the stay wires, and thereby 75 hold the stay wires against slipping when the mesh body is hit with a glancing blow by a vehicle. The wires 15 are preferably not welded to the stay wires because such welding would injuriously affect their strength and yielding qualities, and 80 furthermore would rigidly hold them against shifting lengthwise of themselves relative to the stay wires.

As shown in Figs. 2 and 3, the wires 15 and 17 pass around a metal plate 18 that is secured to 85 the corner of the end post 12, and the ends of such wires extend through diametral holes in adjusting pins or bolts 19, which are mounted on an angle plate 21 that is secured to the end post 12. The pins are shouldered as at 22, and their 90 shank portions, of reduced diameter, extend through the bar 21. When nuts 23 are screwed up, the shoulders 22 are clamped tightly against the bar 21, so that the pins 19 are frictionally held against turning. However, the pins can be 95 turned by a wrench applied to their outer ends to wind the wires thereon, and maintain said wires taut. This taut condition is more effectively maintained by reason of the individual anchoring of the wires than if the wires were all connected 100 as a unit by a single clamp.

In Figs. 4 and 5, the strand wires 15 extend through holes in the flange 24 of an anchoring plate 25, and their ends are upset. The wires may be inserted into the flange 24 after the flange is 105 in place, the said wires being individually maintained under tension, while upsetting or riveting their ends, or they may be connected to the flange 24 and the plate 25 then drawn into position on the post and bolted thereto.

In Fig. 6, I have shown the strand wires 15 as having their ends inserted through holes in a bar 26, with the ends of the strands upset to securely anchor them to the bar. This work may be done 5 at the factory, and the mesh with the bars 26 attached brought to the place of installation, the bars 26 being fastened to the angles 25a by means of bolts 26a, the nuts of the bolts being drawn up to place the mesh under the tension desired.

10 Referring to Figs. 7 and 8, I show the manner in which the band 10 is connected to the intermediate posts 11. This connecting means includes a bar 27, preferably of channel form, that is bolted to the post. A coil spring 28 is held in 15 position on the post by the bar 27, the bar being provided with transverse grooves to receive turns of the spring 28, and the upper and lower ends of the spring 28 being turned inwardly as at 29, to prevent the spring creeping or rotating about its 20 axis. The axis of the spring is on a vertical line, and the spring is of approximately oval form when viewed in plan or horizontal cross section, instead of being of cylindrical contour as is common in coil springs. Of course, the springs as a 25 whole may be of cylindrical contour, but the oval form may be preferred, for the reasons herein-after set forth. Also, the stock of which the spring is formed may be of either rectangular cross section or cylindrical.

30 A clamping bar 31 is disposed within the spring adjacent to the outer or front side thereof, and a clamping plate 32 is held in place by bolts 33 which draw the plate 32 and the bar 31 together to clamp them firmly on the spring 28. The bolts 33 also 35 retain an outer clamping plate 34 in position to hold the wire band 10 securely against the plate 32.

The plate 32 is provided with beads or ribs 35 at its edges that serve as curved bearing surfaces 40 for the strands 15, and also cause deflection of such strands. By this means the band is deflected in a horizontal direction across the entire vertical width thereof, so that it forms a curve on either side of the clamp connecting the said 45 straight portion to the band. When the band contracts through lowering of temperature, these curves tend to straighten out, but when the temperature rises, the spring quality of the wire restores the curves and keeps the band taut.

50 While the wires 15 and 16 may be of any suitable gauge and spacing, depending upon conditions to be met, I have shown the wires 15 as being of approximately 8 gauge and spaced apart $\frac{1}{2}$ inches center-to-center, while the stay wires 16, if employed singly may be of 9 gauge, and if mounted in pairs as shown in Fig. 6, may be of 10 gauge, the spacing between the stay wires being approximately 4 inches.

The strand wires 15, being of spring steel, have 60 considerable inherent elasticity, and this elasticity or spring-like character is increased by reason of the deflections of said wires at the stay wires and at their points of connection to the plates 32 and 34, so that they will remain taut notwithstanding the repeated changes in temperature as 65 between summer weather and winter weather.

The springs 28 also assist in maintaining the wires uniformly taut throughout their lengths. That is, there will not be a tendency for over-tension between two posts 11, and sagging between two adjacent posts.

Furthermore, the springs 28 serve to transmit the stresses of impact throughout the length of the band, and also serve as cushioning elements when impact is had against the structure at points adjacent to the posts.

80 The oval or elliptical form of the springs 28 facilitates movement of the outer sides of the springs in directions longitudinally of the mesh when pressure is exerted on the mesh at points between the posts, thereby readily transmitting stresses from the section between two posts to the other posts and increasing the elasticity of the structure as a whole. For example, in a structure wherein the posts are 16 feet apart, the mesh may be deflected laterally as much as 2 ft. at 90 points between the posts, and will nevertheless return to its original position. The resistance to deflection, of course, increases rapidly as the degree of deflection increases, and the mesh is capable of absorbing very great stresses, as compared to mesh structures of ordinary wire, and those wherein special provision is not made for transmitting the stresses from one section to another.

95 In Fig. 10, I have shown a spring 28a which 100 may be utilized instead of the helical coil 28, such spring consisting of a band whose rear ends are bolted to the posts 11 by a clamping bar or by bolts extending directly through the holes in the rear side of the spring. The mesh would be 105 fastened to the front side of the spring by suitable clamping plates, such as 31, 34 and 35, and bolts 33. The springs 28a can be of any axial length desired, depending upon whether a single 110 spring is desired, or a series of narrow bands 28a.

115 It will be understood that various features of my invention such as the springs 28 and 28a, and the clamping members, as well as the anchoring means at 25 and 25a are applicable also to guard bands consisting of sheet metal or spring steel bands, instead of wire mesh.

I claim as my invention:—

1. A guard fence comprising a support, an impact-receiving band, a helically-wound spring secured at one side to said support, with its axis approximately vertical, and means for securing the band to the other side of said spring.

120 2. A guard fence comprising a support, an impact-receiving band, a helically-wound spring secured at one side to said support, with its axis approximately vertical, and means for securing the band to the other side of said spring, the spring being of elliptical contour with respect to its axis.

125 3. A guard fence comprising posts, a wire mesh having strand wires extending in horizontal directions, a spring of approximately annular form having its axis vertically disposed, means for securing the rear side of said spring to one of the supports, a bar disposed within said spring, adjacent to the outer side thereof, a clamping plate against the outermost surface of the spring and secured to said bar, the said plate having vertically-extending beads adjacent to its edges, and an outer clamping plate overlying the wire and holding the same against the outer face of the second-named clamping plate, and of such narrow width as to deflect the wire into the space between the said beads.
